(57) **CLAIM**

The ornamental design for an ammunition reserve indicator, as shown and described.

DESCRIPTION

FIG. 1 is a back plan view of the ammunition reserve indicator in accordance with our invention;
FIG. 2 is a top plan view thereof;
FIG. 3 is a right side plan view thereof;
FIG. 4 is a bottom plan view thereof;
FIG. 5 is a front plan view thereof;
FIG. 6 is a left side plan view thereof; and,
FIG. 7 is a perspective view of the ammunition reserve indicator in an assembly.
The dashed lines are included for the purpose of illustrating structure and form no part of the claimed design.
